(57) **CLAIM**

We claim the ornamental design for an illuminated valve position indicator, as shown and described.

DESCRIPTION

FIG. 1 is a perspective view from the front showing our design with the illuminated valve position indicator in the “OPEN” position.

FIG. 2 is a top view thereof showing our design with the illuminated valve position indicator in the “OPEN” position. FIG. 3 is an underside view thereof.

FIG. 4 is a left side view thereof showing our design with the illuminated valve position indicator in the “OPEN” position and the other side is a mirror image.

FIG. 5 is a front view thereof showing our design with the illuminated valve position indicator in the “OPEN” position and the other side is a mirror image.

FIG. 6 is a perspective view from the front showing our design with the illuminated valve position indicator in the “CLOSED” position.

FIG. 7 is a top view thereof showing our design with the illuminated valve position indicator in the “CLOSED” position.

FIG. 8 is a left side view thereof showing our design with the illuminated valve position indicator in the “CLOSED” position and the other side is a mirror image; and,

FIG. 9 is a front view thereof showing our design with the illuminated valve position indicator in the “CLOSED” position and the other side is a mirror image.
